UNITED STATES PATENT OFFICE.

ABRAM REESE, OF PITTSBURG, PENNSYLVANIA.

CAR-STOVE.

SPECIFICATION forming part of Letters Patent No. 269,324, dated December 19, 1882.

Application filed July 24, 1882. (No model.)

To all whom it may concern:

Be it known that I, ABRAM REESE, of Pittsburgh, in the county of Allegheny and State of Pennsylvania, have invented certain new and useful Improvements in Car-Stoves; and I do hereby declare that the following is a full, clear, and exact description of the invention, which will enable others skilled in the art to which it appertains to make and use the same, reference being had to the accompanying drawings, which form a part of this specification, in which—

Figure 1 is a longitudinal section of one end of a railway-car with my improvements shown partly in section. Fig. 2 is a plan view of the trigger. Fig. 3 is a plan view of the stove. Fig. 4 is a detail; Fig. 5, another. Fig. 6 is a detail view, showing the valve in its elevated position.

20 In Letters Patent No. 142,867, granted to me September 16, 1873, I have shown a car-stove so arranged with relation to a reservoir of water and a valve that the crushing in or breaking of the shell of the car caused the valve to instantaneously open and discharge the contents of the reservoir into the stove, and thereby extinguish the fire.

30 My present invention concerns certain improvements in the device already patented by me, as stated, and has for its objects a more effective mode of operation, better distribution of the discharging water, and the extinguishing of the fire not only by the crushing in or breaking of the shell of the car, but also by the collapse of the platform or the derailment of the wheels.

The invention consists in the combination and arrangement of parts, all substantially as hereinafter fully described and claimed.

40 A designates the stove, which may be of any of the usual forms for coal-burning. The smoke-pipe B passes up from the back of the stove to the roof C. D is the end of the car, E its platform, and F its bed. Above the 45 stove I place the air-chamber G, to prevent undue evaporation, and on top of this I place the reservoir H, having means for filling conveniently. The bottom of the reservoir H is formed into a valve-seat, a, for the downwardly-closing valve b, whose stem c passes up through the cross-bar d of a frame, E. Above bar d a

spiral spring, f, is placed on stem c, and compressed by the head g of the stem, so that, if free, valve b will open upwardly.

To the upper ends of the frame E, I pivot at 55 h' h' the elbow-crank levers h h, so arranged that when their upper ends are drawn inwardly their other ends press downwardly upon the head g of the stem c and force the valve to its seat. This drawing together of the levers h, I 60 effect by a flexible wire cord, i, (or equivalent connection,) which passes thence up through cover k of the reservoir, to and over a sheave, l, attached to the roof C, whence it descends through the floor or bed F to the tripping devices under the car. These are as follows: At a point about over the rail I attach to the bed of the car a hanger, m, having the branch n, both bifurcated for the trigger o. The trigger is pivoted in branch n of hanger m, which latter 70 guides it vertically, and its end is widened into the shoe p, as shown. A bracket, q, is attached to the car-bed, having in its lower portion a socket, r, (see Fig. 4,) into which fits a projection on the keeper s, whose upper end is attached to the wire cord i. Keeper s below 75 passes down between the forked end of trigger o, and has a cross-pin, t, beneath it, as shown. Cord i is tightened so as to hold valve b closed, being drawn laterally by cord u, connected to car end D, again by the cord v to the timbers of platform E, and thus holding the keeper s up against the bracket q. The cord i will be slackened and the fire extinguished by flooding if the platform or bed 80 collapse, if the end of the car be crushed in or broken, if the roof be caved in, or if the wheels leave the rails. This latter accident instantly causes shoe p to press upon the rail, tilting up that end of trigger o and depressing the other 85 end, and with it the keeper s, which, as soon as it is free from its seat in bracket q, swings loose and relaxes the cord i. This releases the tension of the bifurcated cord i, allowing the levers h h to swing around on their pivots and 90 permitting the valve b to rise up from the seat, thus admitting the water from the reservoir D.

The top plate of the stove constituting the bottom J of the air-chamber, is perforated with a series of holes, increasing in size from the 95 center outwardly, (see Fig. 3,) and they are bored so as to diverge downwardly and effect

the desired distribution of the water over the whole surface of the fire in the stove. By increasing the size of the holes toward the outer rows, the water is discharged to the best advantage, as the smaller holes at the middle will not allow all the water to pass straight down. I thus insure a uniform discharge of water over all the coals. The adjusting cord or loop *u*, after being drawn tight, is locked by the padlock *w* or similar device to prevent tampering.

To avoid wanton or untimely action of the trigger, I insert a wire through hanger *m* just above the trigger. While this prevents movement of the trigger in all ordinary circumstances, it will be instantly sheared off when the wheels leave the rails, and thus allow the devices to operate.

I claim as my invention—

- 1. In a railway-car, the combination of a stove, a reservoir containing water above the level of the stove, a spring-opened valve closing said reservoir, and a flexible cord connected to said valve at one end and at the other to the platform-timbers of the car, substantially as described, whereby collapse of the platform relaxes the cord and opens the valve.

2. In a railway-car, the combination of a stove, a reservoir containing water above the level of the stove, a spring-opened valve closing said reservoir, a flexible cord connected to said valve, and a tripping device under the car connected to said cord, and adapted to be operated to relax the cord by impact of the rail, substantially as described.

3. In a railway-car, the combination of stove *A*, air-chamber *G*, reservoir *H*, spring-closing valve *b*, frame *e*, levers *h*, and flexible cord *i*, substantially as described.

4. In a railway-car, the combination, with *A* stove *A*, of the reservoir *H*, chamber *G*, and plate *J*, having divergent perforations increasing in size from the center outwardly, substantially as set forth.

5. The combination, with valve *b*, of the cord *i*, bracket *q*, keeper *s*, having pin *t*, trigger *o*, and hanger *m* *n*, substantially as described.

In testimony that I claim the foregoing as my own I have hereto affixed my signature in presence of two witnesses.

ABRAM REESE.
